UNITED STATES PATENT OFFICE.

JOHN B. HORAN, OF PITTSBURGH, PENNSYLVANIA, ASSIGNOR TO JOHN A. HANLON, OF PITTSBURGH, PENNSYLVANIA.

WORK-HOLDER FOR COATED ARTICLES.

1,290,202.

Specification of Letters Patent.

Patented Jan. 7, 1919.

Application filed April 23, 1918. Serial No. 230,248.

To all whom it may concern:

Be it known that I, JOHN B. HORAN, a resident of Pittsburgh, in the county of Allegheny and State of Pennsylvania, have invented a new and useful Improvement in Work-Holders for Coated Articles, of which the following is a specification.

This invention relates to holders for coated articles which are to be coated and then subjected to centrifugal action to remove surplus coating. The device is particularly designed for holding galvanized metal articles while dipping and thereafter subjected to centrifugal action to remove the surplus coating material.

The object of the invention is to provide a holder for the purpose specified which is of simple construction, and wherein the various articles are kept separate, whereby a uniform coating is assured.

The invention comprises a device constructed and arranged as hereinafter described and claimed.

In the accompanying drawing, Figure 1 is a side elevation of the device; Fig. 2 is a vertical section thereof on the line 2—2 of Fig. 3 showing several articles to be coated therein and with a surrounding jacket; Fig. 3 is a plan view of the same; and Fig. 4 is a vertical section of the lower part of the device showing additional means for supporting the articles to be coated.

The work-holder illustrated is adapted particularly for holding long articles, such as bolts, spikes, nails or other relatively long articles provided with an enlargement at one end, or unheaded articles, such as bars, strips, or the like. The holder comprises two members 1 and 2 suitably spaced apart and provided with a series of openings or holes 3 in line with each other for receiving the articles to be coated. These two members are illustrated in a form of circular plates or disks having holes punched therein, but obviously they can be of any shape or structure having alining openings for receiving the articles to be coated. These members are held in proper spaced relation to each other, by means of a number of tie rods or bolts 4, four such bolts being shown, which pass through openings in the disks and by means of their heads and nuts tie the disks together, the disks being held separated the proper distance by means of

tubes 5 surrounding said bolts. These bolts and separating tubes provide simple means for rigidly holding the disks in proper spaced relation, and also enable the disks to be readily placed different distances apart, to accommodate articles of various lengths, by simply substituting longer or shorter bolts and separating tubes than the ones illustrated.

These disks are provided with suitable means for attachment to the rotating member of a centrifugal machine. As shown the lower disk is provided with a round hole for the passage of the shaft 6 of the centrifugal machine, and the upper disk is provided with a square hole 7 which is engaged by the pyramidal end 8 of the vertical shaft 6. As the centrifugal machine may be of any construction it is not illustrated and need not be described. Suffice to say that the shaft 6 is rotated at a high speed, and when the holder is set onto it, it is also rotated at a high rate of speed, and the unbalancing due to the rotary action holds it firmly on the end of the rotating shaft, without any further attaching means.

In the drawings the articles to be coated are shown at 10, in Figs. 1 to 3 being illustrated as bolts, which are slipped down through the alining openings in the disks 1 and 2, and are held from falling through by means of their heads. When coating bolts the disks will be spaced such a distance apart that the threaded ends of the bolts project entirely below the lower disk and therefore will not be liable to be battered or marred, and all excess metal is thrown off so as not to fill the thread.

For coating articles not provided with heads, other supporting means therefor are provided. Fig. 4 shows one arrangement for this purpose, in which a foraminous supply member 11 is supported below the lower disks and serves as a rest for the articles. Preferably this supporting member will be so formed that the articles rest on projecting portions or points so as to permit the coating material draining off. In case the articles are provided with holes through their ends, they can be supported by a rod or wire threaded therethrough.

Suitable means are also provided for lifting and handling the work-holder, this being shown in the form of a loop or bail 12

attached to the upper disk 1, either hingedly or rigidly, and so formed that it can be engaged by a crane or any other suitable lifting means or device.

5 In the use of the device (the disks having been spaced apart a distance adapted to the length of the articles to be coated) the holes in the disks are filled by dropping uncoated articles thereinto. The holder is then lowered down into the galvanized tank, moved around therein and held therein for the desired time, and is then withdrawn and carried to and set down on the upper end of the centrifuge shaft 6, whereupon the 10 centrifuge is started, thus imparting a high rotary speed to the holder and throwing the excess amount of coating material off the articles. A jacket 13 surrounding the holder will be used to catch the excess coating material and prevent it being thrown into the 15 room.

Since none of the work-holding holes are at the axis of rotation, all of the coated articles are subjected to the centrifugal action, 20 which removes the surplus coating material and leaves a smooth uniform coating thereon. Since the articles are not in contact at any time, either during dipping or while rotating, a very uniform coating is secured, 25 and furthermore threads or other delicate parts of the articles are not liable to injury.

Various changes may obviously be made in the form and construction of the parts without departing from the invention as defined 30 in the claims hereinafter appearing.

What I claim is:

1. A holder for articles while dipping and subjecting to centrifugal action, comprising a pair of spaced members provided with 35 alining means for holding the articles to be coated separated from each other, said mem-

bers being provided with means for connection to a centrifugal machine.

2. A holder for articles while coating and subjecting to centrifugal action, comprising 40 a pair of spaced members provided with alining openings to receive individual articles, said members being provided with means for connection to a centrifugal machine. 45

3. A holder for articles while coating and subjecting to centrifugal action, comprising a pair of members provided with alining openings to receive the articles to be coated, and tie rods and separators connecting said 50 members and spacing the same apart, said members being provided with means for connection to a centrifugal machine. 55

4. A holder for articles while coating and subjecting to centrifugal action, comprising 60 a pair of members provided with alining openings to receive the articles to be coated, tie bolts and separating tubes connecting said members and spacing them apart, said members being provided with means for 65 connecting the same to the shaft of a centrifugal machine, and means on said device for the attachment of lifting mechanism. 70

5. A holder for articles while coating and subjecting to centrifugal action, comprising 75 a pair of spaced members provided with alining openings to receive the articles to be coated, one of said members being provided with a non-circular hole, in combination with a centrifuge shaft having a non-circular 80 pointed end to engage said hole.

In testimony whereof, I have hereunto set my hand.

JOHN B. HORAN.
